Specification for Design.

Patented Mar. 7, 1922.

Application filed June 6, 1921. Serial No. 475,454. Term of patent 3½ years.

To all whom it may concern:

Be it known that I, BENJAMIN NATHAN, a citizen of the United States, residing at New York, in the county and State of New York, have invented a new, original, and ornamental Design for a Textile Fabric, of which the following is a specification, reference being had to the accompanying drawing, forming part thereof.

The figure is a plan view of a portion of a textile fabric illustrating my new design.

I claim:

The ornamental design for a textile fabric, as shown.

In testimony whereof I have hereunto set my hand and seal in presence of two subscribing witnesses.

BENJAMIN NATHAN. [L. S.]
